US0D1043600S

(12) **United States Design Patent** (10) **Patent No.:** **US D1,043,600 S**
(45) **Date of Patent:** **** Sep. 24, 2024**

(54) **DISPLAY DEVICE**

(71) Applicant: **Samsung Display Co., Ltd.**, Yongin-si (KR)

(72) Inventor: **Junsu Choi**, Yongin-si (KR)

(73) Assignee: **Samsung Display Co., Ltd.**, Yongin-si (KR)

(**) Term: **15 Years**

(21) Appl. No.: **29/853,644**

(22) Filed: **Sep. 16, 2022**

(30) **Foreign Application Priority Data**

Mar. 16, 2022 (KR) 30-2022-0010240

(51) **LOC (14) Cl.** **14-03**

(52) **U.S. Cl.**

USPC ..... **D14/138 AB**; D14/345

(57) **CLAIM**

The ornamental design for a display device, as shown and described.

DESCRIPTION

FIG. 1 is a perspective view of the display device in a folded state with the rear cover extended;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of the display device in a folded state with the rear cover retracted; and,

FIG. 9 is a perspective view of the display device in an unfolded state with the rear cover retracted.

The broken lines in the drawings represent portions of the display device that form no part of the claimed design.

1 Claim, 9 Drawing Sheets
